CLAIM

The ornamental design for a coffee machine, as shown and described.

DESCRIPTION

FIG. 1 is a perspective view of a coffee machine according to my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of part 9 as shown in FIG. 1; and, FIG. 10 is an enlarged view of part 10 as shown in FIG. 2. The short dash broken lines in the drawings depict portions of the coffee machine that form no part of the claimed design.

The shade lines in the figures show contour and not surface ornamentation.

The long dash-short dash broken lines in the drawings depict the boundaries of the enlarged views and form no part of the claimed design.
